CLAIM

The ornamental design for a cross tee pipe fitting, as shown and described.

DESCRIPTION

FIG. 1 is a perspective view of a cross tee pipe fitting showing our new design;

FIG. 2 is a top plan view thereof, the bottom, right and left sides being the same as the top shown; and

FIG. 3 is a front elevational view thereof, the rear being the same as the front shown.

FIG. 1

FIG. 2

FIG. 3
